UNITED STATES PATENT OFFICE

98,803

DESIGN FOR AN ASHTRAY

Lester K. Franklin, Chicago, Ill.

Application September 7, 1935, Serial No. 58,464

Term of patent 3½ years

To all whom it may concern:

Be it known that I, Lester K. Franklin, a citizen of the United States of America, residing at 2535 Greenvew Avenue, Chicago, Illinois, have invented a new, original, and ornamental Design for an Ashtray, of which the following is a specification, reference being had to the accompanying drawing, forming a part thereof.

Fig. 1 is a side perspective view; Fig. 2 is a front view; and Fig. 3 is a top perspective rear view of an ash receiver showing my new design.

The characteristic feature of my design resides in an ashtray mounted on a base with a miniature sail boat ornament in the background and also mounted on the base.

I claim:

The ornamental design for an ashtray substantially as shown and described.

LESTER K. FRANKLIN.
